The ornamental design for a figurine, as shown and described.

DESCRIPTION

FIG. 1 is a top front isometric perspective view of a figurine showing our new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The evenly-spaced broken lines and unshaded areas in the figures illustrate portions of the article's appearance that form no part of the claimed design. The long and short broken lines define bounds of the claimed design and form no part thereof.

The shading is provided merely to represent contours of the design and does not connote the character of the surfaces such as any specific texture, material, gloss, translucence, transparency, surface treatment, or surface decoration.
